UNITED STATES PATENT OFFICE.

WILLIAM J. BRADLEY, OF TROY, AND JOHN MATHISEN, OF LANSINGBURG,
NEW YORK.

DESIGN FOR A METAL BAR.

SPECIFICATION forming part of Design No. 27,757, dated October 19, 1897.

Application filed May 10, 1897. Serial No. 635,957. Term of patent 14 years.

To all whom it may concern:

Be it known that we, WILLIAM J. BRADLEY, residing at Troy, and JOHN MATHISEN, residing at Lansingburg, county of Reusselaer, 5 State of New York, citizens of the United States, have invented and produced a new and original Design for a Metal Bar, of which the following is a specification, reference being had to the accompanying drawings, forming 10 part thereof.

Figure 1 of the drawings is a plan view of a metal bar embodying our design. Fig. 2 is an end view of the same, which serves also to illustrate the cross-sectional form of the bar.

15 The bar is of elongated form, as shown in Fig. 1, and has the bottom surface A and the side surface B approximately plane and intersecting each other to form an acute angle at C. The upper side of the bar comprises the 20 approximately plane surface D, the convexed surface D', and the reversely-curved surface D² D³. The convexed surface D' intersects the bottom plane surface at A', and the convexed portion D² of the reversely-curved surface 25 intersects the approximately plane side surface at D⁴, forming an approximate right angle. The plane upper surface D is approximately parallel with or slightly inclined to

the bottom plane surface A, and connects the convexed surface D' with the concaved portion D³ of the reversely-curved surface, being tangential to both of the connected curved surfaces.

The leading feature of the design consists of the elongated bar having the approximately 30 plane surfaces A and B intersecting at C to form an acute angle, the convexed surface D' intersecting the plane surface A at A', the reversely-curved surface D² D³, with its convexed portion, intersecting the plane side surface B approximately at right angles, and the upper plane surface D connecting the convexed surface D' with the concaved portion of the reversely-curved surface, as shown.

What we claim as new, and desire to secure 45 by Letters Patent, is—

The design for a metal bar herein shown and described.

In testimony whereof we have hereunto set our hands this 8th day of May, 1897.

WILLIAM J. BRADLEY.
JOHN MATHISEN.
